UNITED STATES PATENT OFFICE.

EMMA V. FRENCH, OF HOOPESTON, ILLINOIS.

STREET-SWEEPER.

1,371,885.

Specification of Letters Patent. Patented Mar. 15, 1921.

Application filed July 25, 1919. Serial No. 313,272.

To all whom it may concern:

Be it known that I, EMMA V. FRENCH, a citizen of the United States, residing at Hoopeston, in the county of Vermilion and State of Illinois, have invented new and useful Improvements in Street-Sweepers, of which the following is a specification.

The object of the invention is to provide a device carried on an autovehicle chassis by means of which it is operated for the purpose of sweeping the street and depositing the results of the sweepings in a suitable receptacle carried by the chassis. The receptacle is susceptible of being handled by an operator for the purpose of adjusting it with reference to the ground or pavement over which the device may be moved and this means of adjustment also serves to position the brushing medium as desired with respect to the ground. Aside from this adjustment which is handled by the operator, means is provided for adjusting the brushing member relative to the receptacle.

A further object of the invention is to provide an automobile street sweeper which is simple in construction, durable and effective in operation and inexpensive to manufacture.

Other and further objects appear in the following description wherein the invention is set forth in detail.

To the exact construction in which it is shown and described the invention is not to be restricted. The right is reserved to make such changes or alterations as the actual reduction to practice may suggest, in so far as such changes or alterations are compatible in spirit with the annexed claim.

The same numerals of reference designate the same parts throughout the several figures of the drawing, wherein:

Figure 1 is a top plan view of an autovehicle street sweeper constructed in accordance with the invention,

Fig. 2 is a side elevational view of the sweeper apparatus *per se*.

Fig. 3 is a perspective view of the receptacle forming part of the invention.

As shown, the invention is a street sweeping apparatus designed for mounting on an autovehicle chassis as that indicated in the drawings and designated by the numeral 1, this chassis having the usual traction wheels 2. On the rear axle of the chassis there are mounted the brace bars 3, one on each side of the chassis but positioned on the inner

side of the side rails thereof and supported at their forward ends by depending bars 3'. The one bar 3 is longer than the other and each carries at its terminal a laterally projecting stud 4. The two studs 4 are axially alined and since the one bar 3 is shorter than the other the axial line of the studs 4 is diagonally disposed with reference to the chassis. This construction is provided for the purpose of disposing the brush and receiving apparatus in a diagonal position, such as is common in street sweeping apparatus. This sweeping or cleaning apparatus comprises a receptacle 5 which is closed on all sides but the front side. The bottom of the receptacle is of greater width than the top and the end plates or walls of the receptacle, therefore, have their forward edges diagonally disposed, as clearly shown in Figs. 2 and 3 of the drawings. The receptacle 5 is swung from the studs 4 carried by the bars 3 and to this end hinge elements 6 are provided and attached to the receptacle on top adjacent the rear edge thereof, these hinge elements engaging the studs and thus providing for pivotal movement of the receptacle with reference to the chassis.

In order that the receptacle may be raised and lowered as desired by an operator who will sit in the seat 7 indicated in dotted lines in Fig. 1 there is provided a hand operated lever 8 which is pivotally mounted on the chassis frame, this hand lever being provided with a spring latch 9 engageable with any one of the teeth of the sector 10 also mounted on the frame with its arcuate portion concentric with the pivot point of the lever as is common practice in such construction. The lever 8 has connected with it an arm 11, the end of which pivotally connects with one end of a connecting rod 12 whose remaining end pivotally connects with an ear 13 attached on top of the receptacle adjacent the forward end at one side of the latter. Obviously the operation of the lever 8 will serve to raise or lower the forward end of the receptacle, the studs 4 acting as the pivot points of movement of the receptacle in this raising and lowering operation.

Rollers 14 are attached to the receptacle at opposite ends and approximately at points falling within the center line of the bottom of the receptacle. These rollers are designed to engage the ground or pavement when the receptacle is in operative position—that is, when it is in position to receive the refuse

accumulated by the brush which forms a part of the invention.

On opposite ends of the receptacle there are provided arms or bars 15 which are pivoted, as indicated at 16, to the end plates of the receptacle adjacent the rear side thereof. These arms extend forwardly and support between them a cylindrical brush 17 which stands normally before the front open side of the receptacle. Adjacent the forward side but formed in the end plates of the receptacle there are the perforations or eyes 18, each plate having a set of these eyes formed in an arc whose center is the center 15 of the pivot point 16. Bolts 19 pass transversely through the arms and may be engaged in any one of the series of holes 18, so that the brush may be raised or lowered with reference to the receptacle. Thus if 20 the bristles on a brush wear, it may be lowered and still have the same relative position with respect to the receptacle that it had when new.

The brush 18 is designed to be rotated by 25 one of the traction wheels 2 and to this end is equipped with a sprocket 20 over which a chain 21 is trained, the chain 21 also being trained over a sprocket 22 which is mounted on a supplemental shaft 23, this shaft including 30 a universal joint 24, so that the two parts of the shaft may be journaled in the bearings 25 and 26 mounted on top of the receptacle but disposed with their axes in different planes, so that that section of the 35 shaft which is carried in the bearing 26 carries a sprocket wheel 27, while one of the traction wheels 2 carries a sprocket wheel

28, a chain 29 operatively connecting these two sprocket wheels. Obviously the rotation of the traction wheels will impart a 40 rotary motion to the supplemental shaft 23 and this motion will be transmitted to the brush which wiping upon a street or pavement will sweep the refuse gathered into the receptacle. 45

The hand lever 8 provides means for raising the brush to lift it out of engagement with the street or pavement and the receptacle thereby is elevated at its forward or open side so that it may retain therein the 50 refuse which was gathered when the brush was engaging the ground.

The invention having been described, what is claimed as new and useful is:

In a machine of the kind described, the 55 combination with a chassis having traction wheels, of a receptacle swingingly supported from the chassis, the front side of the receptacle being open, arms pivotally mounted on opposite ends of the receptacle, a brush supported by the two arms, the brush being rotatably mounted in the arms and disposed in front of the open side of the receptacle, the receptacle having a series of holes formed in the ends adjacent the open side, 60 65 bolts passing through the arms and attachable in any of the holes of the series, whereby the brush may be raised or lowered with reference to the receptacle, means for rotating the brush, and means for raising and 70 lowering the forward end of the receptacle.

In testimony whereof I affix my signature.

EMMA V. FRENCH.
